SLIDE-RULE PENCIL

Robert C. Magee, Dayton, Ohio

Application March 9, 1945, Serial No. 581,886

5 Claims. (Cl. 235—70)

1

My invention relates to devices which are usable both as a pencil and as a slide-rule and which may be conveniently carried around in the pocket, the same as a pencil or fountain pen; and its object is to provide certain improvements thereto and more particularly to provide means whereby the movable parts of such a device may be easily and quickly locked together so as to be held against relative movement when the device is used as a pencil.

In the drawing,

Fig. 1 is a view in side elevation of a device embodying my invention;

Fig. 2 is a view thereof in longitudinal section on a larger scale; and

Fig. 3 is a view in transverse section taken on a plane indicated by the line 3—3 in Fig. 2.

The pencil 10 may be of any type or indeed any writing implement whatever; as shown herein, it is a lead refillable pencil having a magazine 11 for the storage of new leads, which magazine is closed by a stopper 12 on the end of which an eraser 13 may be provided. The pencil, as shown, is also preferably provided with a raised portion 14 (Fig. 3) on its periphery for a purpose presently to be referred to. Closely fitted around the pencil and movable longitudinally therewith is a tubular member or slide 15 which may, if desired, extend practically the entire length of the pencil and which has a longitudinal slot 16 through which the surface of the pencil is visible. The visible portion of the pencil is marked lengthwise with a scale (as indicated in Fig. 1) suitably graduated to serve as one of the scales of a slide-rule. There may also be marked on the tubular slide along one or both of the edges of the longitudinal slot 16 thereof, graduations appropriate for use as scales of a slide-rule in cooperation with the scale marked on the pencil. The raised portion 14 of the pencil projects into the slot 16 and its purpose is to prevent relative rotary movement between the tubular slide and the pencil so as to keep the scale on the pencil in register at all times with said slot. Said raised portion may have, and preferably has, the form of a longitudinal ridge extending the full length of the pencil and exactly fitting said slot; and in such case the scale carried by the pencil is marked upon this ridge.

Movably embracing the tubular slide 15 is a cursor having a transparent portion 17 marked with an index-line or lines 18 and through which the respective scales of the tubular slide and pencil are visible. Said cursor is provided with means to lock it and the pencil and tubular-slide.

2

immovably together so that when the device is used as a pencil there can be no relative movement between these parts. Such locking means may comprise a spring finger 19 of which one end 5 is secured to the cursor and the other end carries a locking lug or pin 20. The tubular slide 15 is provided at its upper end with an annular shoulder 21 which limits the movement of the cursor toward that end, as shown in Fig. 2, and, 10 near said shoulder, with a hole 22 which, when the cursor is in the position shown in that figure, registers with said locking lug or pin; and the pencil has a recess 23 with which the hole 22 also registers when the parts are in the position shown in Fig. 2. Through means, such as a thumb-slide 24, movable upon the cursor and having a projection 25 which rides along the spring finger 19 when the thumb-slide is moved forward, said locking lug or pin may be caused, 15 when the parts are in the position shown in Fig. 2, to pass through the hole 22 in the tubular-slide 15 and into the recess 23 of the pencil, thus locking the cursor, tubular slide and pencil immovably together; and when the thumb-slide is 20 retracted to its rearward position, that is the position shown in Fig. 2, the spring finger 19 causes the locking pin 20 to be withdrawn from its locking position so as to permit the free movement again of the tubular-slide 15 along the pencil and of the cursor along both the tubular-slide and pencil. The tubular-slide may be provided with a longitudinal groove 26 in which the spring finger 19 rides to prevent the cursor from turning around said slide, whereby the transparent portion 25 of the cursor is maintained at all times in proper relation to the scales marked on the pencil and slide respectively.

Finally, a pocket clip 27 may be secured to the cursor as shown, whereby said clip is held immovable on the device when the cursor is locked in position thereon. Thus, through a single movement of the thumb-slide the pocket-clip, cursor and tubular-slide are all three immovably fixed to the pencil.

45 I claim as my invention:

1. In a device of the class described, a pencil having a scale marked lengthwise thereon, a tubular-slide movable along the pencil and having a longitudinal slot registering with the scale on the pencil, a scale marked along an edge of the slot of the tubular-slide to cooperate with the scale on the pencil, and a cursor movably embracing the tubular-slide and having a transparent portion marked with an index line, in combination with means carried by the cursor to

50 55

lock the cursor tubular-slide and pencil immovably together when the device is used as a pencil.

2. The combination defined in claim 1 and further characterized by this: that the locking means carried by the cursor comprises a spring finger having a locking lug normally held by the finger in its unlocking position, and means cooperative with the finger to move the lug into its locking position.

3. The combination defined in claim 1 and further characterized by this: that the pencil has a recess and the tubular-slide a hole adapted to register with said recess, and that the locking means carried by the cursor has a locking pin which is movable into and out of the recess and through the hole in the tubular-slide.

4. The combination defined in claim 1 and further characterized by this: that the tubular-slide has a shoulder at its upper end to limit the movement of the cursor toward that end, that the pencil has a recess and the tubular-slide a hole adapted to register with said recess, and that the locking means carried by the cursor has a locking pin which registers with the hole in the tubular-slide when the cursor is in its limiting position on the upper end of the tubular-slide.

5. The combination defined in claim 1 and further characterized by this: that a pocket clip is fixed to the cursor whereby the clip is held immovably to the pencil when the cursor is locked to the pencil and tubular-slide.

ROBERT C. MAGEE.
